UNITED STATES PATENT OFFICE.

JAMES R. DUDLEY, OF BESSEMER, ALABAMA.

RAILWAY-SWITCH-OPERATING MECHANISM.

1,397,408.

Specification of Letters Patent. Patented Nov. 15, 1921.

Application filed August 8, 1921. Serial No. 490,677.

To all whom it may concern:

Be it known that I, JAMES R. DUDLEY, a citizen of the United States, residing at Bessemer, in the county of Jefferson and State of Alabama, have invented certain new and useful Improvements in Railway-Switch-Operating Mechanism, of which the following is a specification.

My said invention relates to operating means for railway switches and gates, and to means carried by a locomotive or the like for operating said means to open or close a switch or gate. It is an object of my invention to provide operating mechanism which shall be under control of an approaching train and which shall automatically be reset to open the gate or switch after the train has passed by.

A further object of my invention is to provide a simple and effective trip on a train unit, such as a locomotive or the like, which trip shall be under the control of the engineer.

Another object of the invention is to provide a gate which shall be self-locking in open or closed position.

Referring to the accompanying drawings which are made a part hereof and on which similar reference characters indicate similar parts,

Figure 1 is a side view of the locomotive with my improved trip positioned thereon,

Fig. 2 a plan of a portion of a railway track and a switch adapted to be operated by my improved controlling means,

Fig. 3, a similar view of a railroad crossing and gates therefor, and

Fig. 4 a detail of the gate and its operating mechanism and

Fig. 5 is a detail of trip 44 and related parts.

In the drawings 10 indicates a locomotive of any ordinary type having at its forward end brackets 11 in which are mounted vertically slidable bars 12 carrying at their lower ends segments 13 provided with vertically positioned rollers 14 projecting outward therefrom. The bars are adapted to be operated by bell cranks 15 to which are connected links 16 attached at their other ends to hand levers 17 in the cab of the engine. By operating a lever 17 the corresponding segment 13 may be raised or lowered to operate the mechanism hereinafter described.

A railway 18 (Fig. 2) is provided with a switch 19 having a slidable switch bar 20. A bell crank 21 is attached at one end of the switch bar and a link 22 connects this bell crank to a second bell crank 23 attached to one end of a sliding bar 24. Springs 25 normally hold the bar, and therefore the switch, in the position shown. If a passing locomotive should have its member 13 lowered this will engage the member 26 on bar 24 and throw the switch to its opposite position. The roller bearings 14 on member 13 prevent excessive friction due to contact between members 13 and 26.

The train having passed the switch is now on the track 27 and the segment 13 being left in lowered position will contact with another segment 28 and will restore the switch to the position shown in the drawings, in an obvious manner. Any desirable or conventional means may be used for holding the switch in the position to which it is moved, until one of the bars 24 and 29 is operated to change the position. If the switch is to be left in the opposite position from that shown in the drawings segment 13 will of course be raised as soon as it has operated the bar 24.

Fig. 3 shows an adaptation of the same mechanism for operating a pair of railway gates. In this figure 30 indicates a crossing over the track 31, which crossing may be barred by a gate 32. This gate is carried by a vertical shaft 33. The gate is mounted so as to slide vertically on the shaft 33 to a limited extent and adjacent to said shaft is a segment 37 on which the gate rides, the segment having a low place near each end. One of these low places corresponds to the open position of the gate and the other to the closed position and they form locking devices to hold the gate in open and closed positions by its own weight.

For operating the gates I have provided bars 38 and 39 extending transversely of the track each bar carrying a segment 40 and being held in place by springs 41. If a segment 13 on a train moving in the direction of the arrow (Fig. 3) strikes the left hand segment 40 the bar 38 will be moved to the right, actuating a bell crank 42 and a link 43 connecting the bell crank to a trip 44 beneath the gate, when in open position. This closes the gate which at the end of its travel rides over a lowered front arm of a second

trip 45 and striking against its rear vertical arm, swings the trip to co-act with segment 37 in holding the gate shut.

After the train passes the gate its segment 13 will strike the second segment 40 (unless for any reason the gate is to stay closed) moving the bar 39 to the right and operating through a bell crank 46 and a link 47 to swing another bell crank 48 and 10 actuate the second trip 45. The end of this trip will strike a violent blow against the rear of the adjacent arm of trip 45 and thus return the gate to open position as in Fig. 3.

It will be obvious that a similar gate and 15 operating devices may be provided at the other side of the track, and that gates at each side of the track may have common operating means with connections above or below the track. Similarly, the switch operating 20 mechanism may be duplicated if so desired. Various changes may be made in my mechanism by those skilled in the art without departing from the spirit of the invention or the scope of the appended claims.

Having thus fully described my said invention, what I claim as new and desire to 25 secure by Letters Patent, is:

1. An operating mechanism for railway switches and gates comprising a bar movable transversely of the track, a segmental member fixed thereto, an oppositely facing segmental member carried by a locomotive and vertically positioned rollers on one of said segmental members, substantially as set forth.

2. An operating mechanism for railway switches and signals comprising a series of bars extending transversely of the track, a segmental member on each bar, an oppositely facing segmental member carried by a train unit and adapted to move said bars transversely of the track, connections from one of said bars to move a gate or switch in one direction when it is so moved, and connections from the other bar to the gate or switch for moving the same in the opposite direction, substantially as set forth.

3. In a railway switch operating mecha-

nism, a plurality of bars extending transversely of the track, one of said bars connected to the switch, a segment on another of said bars adapted to co-operate with a similar oppositely positioned segment on a train unit to move the bar, connections from the bar to move the switch to one position when so operated, a segment on another of said bars adapted to be operated by a similar oppositely positioned segment on a train unit and connections therefrom to move the switch to its opposite position when so operated, substantially as set forth.

4. In a railway, a crossing guard mechanism comprising a gate, a shaft providing a vertical pivot therefor, means for holding the gate in open or closed position, bars extending transversely of the track one of said bars being operable by an approaching train for automatically closing the gate and the other being operable by a passing train for automatically opening it, substantially as set forth.

5. In a railway, a crossing mechanism comprising a gate, a shaft providing a vertical pivot therefor, means for holding the gate in open or closed position including trips to engage the free end of the gate, bars extending transversely of the track, connections through one of said bars to said trips whereby the gate may be opened, means on the bar adapted to be operated by an approaching train to actuate the trip, a bell crank connected to the other bar, said bell crank being positioned to strike the other trip and throw the gate into open position, and means on the latter bar adapted for operation by a passing train, substantially as set forth.

In witness whereof, I have hereunto set my hand and seal at Bessemer, Alabama, this 3rd day of August, A. D. nineteen hundred and twenty-one.

JAMES R. DUDLEY. [L. S.]

Witnesses:

ARTHUR L. REYNOLDS,
LEWIS N. CRUMPLER.
